UNITED STATES PATENT OFFICE

CARL C. HAFERKAMP AND WILLIAM J. ELDER, OF OSWEGO, NEW YORK, ASSIGNEES
TO THE DIAMOND MATCH COMPANY, OF CHICAGO, ILLINOIS, A CORPORATION OF
ILLINOIS

MEANS FOR IMPREGNATING MATCH SPLINTS

Application filed October 18, 1928. Serial No. 313,300.

This invention relates to match making machines, and particularly to means arranged in co-operative relation to a match splint carrier whereby the match splints borne by the latter are economically and effectively impregnated with a solution of material adapted to render the splints non-glowing when they, as completed matches, are ignited and the flame is extinguished.

10 The invention may be described as an improvement on the splint impregnating means shown and described in Letters Patent of the United States No. 1,595,189, dated August 10, 1926, which means embodies, amongst other things, a spraying nozzle mounted adjacent the horizontal path of the splint carrier of a match machine and directed toward the travelling depending splints; means for supplying a solution of 20 impregnating material, and also air under pressure, to the said nozzle, and means for oscillating the nozzle in a plane parallel, or substantially so, to the path of the adjacent splints during the travel of the carrier.

25 In the preferred embodiment of the present invention the spraying nozzle is mounted and adapted to oscillate in front of a vertically extending portion of the carrier to the end that the solution will be projected from the nozzle toward and against the horizontally-disposed splints and the opposing vertical face of the carrier plates, thus permitting the resulting moisture on the plates to flow freely therefrom into a suitable drip pan and consequently minimizing the salt accretion and the corrosive action of the solution on the plate. The pendant position of the spraying nozzle ensures the gravitation of the solution thereto from an elevated source of supply. It also enables the suspension of the nozzle from and directly below a horizontal actuating shaft, thus reducing the stresses in the supporting arm of the nozzle as well as in the shaft. Moreover the use of a horizontal actuating shaft obviates the use of thrust bearings therefor, and the location of the bearings and the actuating parts for the shaft above the nozzle, protects the said bearings and parts from the injurious effects of the salt solu-

tion ejected from the nozzle. In this construction there is provided for the spraying element a suitable casing to which access can be readily had, and also means whereby slivers and imperfect splints blown from the carrier plates by the force of the spray escape the nozzle and its operating devices and fall directly upon a detachable screen which is located above the drip pan, whence they can be readily removed.

The invention also comprises novel features of construction and combinations of parts whereby other advantages are gained, as will be hereinafter described; the scope of the invention then being defined in the appended claims.

In the drawings—

Figure 1 is a side elevation of a portion of a continuous match machine equipped with splint impregnating mechanism embodying the principle of our invention.

Fig. 2 is a transverse vertical section, as on the line 2—2 of Fig. 1, the wall of a drip pan hereinafter described being broken away.

Fig. 3 is a horizontal section of the drip pan, detached.

Fig. 4 is a longitudinal vertical section through the casing and the bearing for the actuating shaft of the pendulous spraying element, which element, together with the splint carrier and adjuncts, are in elevation.

Fig. 5 is a vertical section, partly in elevation, of the spraying element.

Fig. 6 is a transverse horizontal section through the sprayer casing, as on the line 6—6 of Fig. 1.

Fig. 7 is a transverse vertical section, as on the line 7—7 of Fig. 6, showing the mechanism for oscillating the sprayer element.

Referring to the drawings, 10 designates a portion of a splint carrier of a continuous match machine which carrier comprises an endless chain of perforated plates in which the splints are endwise inserted and thereby rigidly held in spaced parallel rows. This carrier in its progress to and above the usual paraffin tank 11 is looped over a pair of spaced-apart rails 12 of general U-formation supported by cross-bars 13 carried by the

framework 14 of the machine. The tops of the rails 12 are preferably formed with gaps 15 into which extend a pair of idlers 16 that afford rolling contact for the carrier. These 5 idlers are loosely mounted on a cross-shaft 17 supported by suitably-disposed brackets 18 on the framework. An arched plate 19 supported beneath the path of the carrier loop, in the vicinity of the idlers, serves to 10 intercept and shed waste materials which may fall from the carrier, thus preventing their dropping into the underlying mechanism. This plate 19 is affixed to cross-rods 20 mounted in and between depending lugs 21 on the respective rails 12. (See Fig. 4.)

The leg 22 of the carrier loop, with the rows of match splints projecting horizontally therefrom, travels upward in a vertical path, as seen in Fig. 4, such leg being guided 20 and supported in suitable trackways herein-after described.

Mounted to swing in proximity to and parallel with the path of the upwardly progressing splints, throughout the width of the 25 carrier, is a nozzle 23 by means of which a solution of impregnating material, such as ammonium phosphate, is effectively sprayed upon such splints throughout the width of the carrier. This nozzle is supported at the 30 foot of a pendulous arm 24 fast on a horizontal rock-shaft 25 having its bearings 26 in a suitable housing 27 on an L-frame 28 which is bolted to a pair of transverse frame bars 29. Hence, not only are the stresses in 35 the supporting arm 24 and shaft 25 reduced to a minimum, but the nozzle, as well as the shaft and its operating parts, is away from the path of slivers and broken splints falling from the carrier.

40 The nozzle is provided with solution and air inlet ports 30, 31, respectively, in operative communication with a discharge opening 32 from which the impregnating solution is ejected by air, under pressure. The ports 30, 31 are connected by pipes 33, 34 with ports 35, 36, respectively, in a flanged head 37 which, together with the arm 24, is bolted to a flange 38 on the rock-shaft 25. The port 36 has affixed therein a flexible pipe or hose 50 connection 39 which leads to a suitable source of air supply, and the port 35 has affixed therein a throat member 40 which depends from a bracket 41 bolted, as at 42, to the bearing housing 43 of the L-frame 28. The throat 55 member is connected by means of a pipe 44 with a solution supplying unit which is or may be of the character shown and described in the patent aforesaid. Such unit preferably includes a tank 45 containing impregnating solution which is supplied thereto through a pipe 46 having a suitable shut-off valve 47. It also includes a roll 48 which rotating in the tank and its contents carries up a peripheral film of the solution and delivers 60 it to an inclined trough 49, from which it

flows into a funnel 50 in communication with the pipe 33 and gravitates thence into the port 30 of the nozzle.

From the foregoing it will be seen that during the oscillation of the nozzle 23 air under pressure passes through the port 31 and across the discharge opening 32 of the nozzle, and by contact with the liquid flowing from the port 30 reduces the liquid to a fine spray or mist and projects it in that condition from the mouth of the nozzle and toward and across the vertical splint bearing face of the progressing carrier.

70 The rock-shaft 25 and the roll 48 are concurrently actuated. To this end the rock-shaft is provided with a crank arm 51 which is connected by means of a rod 52 to a crank-disk 53 on a shaft 54 which is geared with the shaft 55 of an electric motor 56 supported on the L-frame 28. The shaft 54 is also 80 equipped with a sprocket wheel 57 which is operatively connected by means of a chain 58 with a similar wheel 59 on the shaft of the roll 48.

85 During the operation of the match machine 90 the moisture deposited on the face of the carrier plates by the spray flows down such plates and drips into a suitable receptacle, thus minimizing the salt accretion and the corrosive action of the solution on the plates, 95 as previously mentioned. This receptacle preferably comprises a pan 60 which underlies the vertical leg 22 of the splint carrier, the pan being provided with basal lugs 61 which are supported on brackets 62 on the framework 100 of the match machine. In one wall of the pan is a pipe fitting 63 affording a fluid passage leading to a lateral overflow pot 64. In this pot is an upstanding nipple 65 which is connected by means of a pipe 66 with the inlet of a suitable pump 67, the outlet whereof is connected by means of a pipe 68 with the solution supply pipe 46 at a level below the valve 47 of the latter. Hence during the 105 operation of the apparatus the liquid flowing into the pan is continuously pumped back to the tank. The tank 45 is provided with an overflow pipe 69 connected with the pipe 66 so that the overflow from the tank passes to the pump and is pumped back to the tank 110 (See Figs. 1 and 2.)

115 The pan 60 is equipped with a detachable rectangular screen 70 upon which fall the slivers, etc., blown from the carrier plates by the force of the spray from the oscillating nozzle, which screen is readily removable for 120 cleaning as occasion may require. The top of the pipe nipple 65 within the overflow pot 64 is so positioned that the solution level in the drip pan is normally well above the screen, 125 thus preventing the crystallization of the impregnating salt on the screen and the consequent plugging of the meshes.

130 A suitable protective casing extends from the drip pan to the top of the loop of the

splint carrier, so as to enclose the adjacent leg 22 of the loop, and also the pendulous spraying element. This casing preferably comprises four substantial corner posts 71, 72 affixed to and rising from the respective sides of the pan. One pair 71 of posts extend adjacent to and parallel with the back of the carrier and terminate in curved portions 73 overlying the adjacent portions of the track rails 12, and the other pair 72 are fastened at their upper ends to the extremities of the curved portions 73, thus affording a rigid skeleton frame. This frame supports the side, front and back walls respectively of the casing, the side walls extending from the bottom to the top of the frame, and the remaining walls terminating at lower levels as seen. The side walls are provided with upper and lower hinged door sections 74, 75, respectively, and the front and back walls 76, 77 are hingedly mounted on the adjacent posts, thus enabling access to be readily had to the interior of the casing for purposes of inspection, repair, etc.

The posts 71 co-operate with spaced vertical guide-strips 78 to afford the trackways hereinbefore mentioned for the leg 22 of the carrier loop in its upward travel, which guide-strips are conveniently fastened, as at 79, to the adjacent side doors 75.

As a simple and efficient means to contribute to the support and guidance of the body of the vertically-moving leg of the carrier loop, spaced-apart vertical guide bars 80 are arranged adjacent the path of the im-perforate front portions 81 (Fig. 6) of the carrier. These bars are fixed at their respective ends to horizontally-disposed U-bars 82 carried by the posts 72 of the casing, the upper bar being suspended by straps 83 depending from the supporting brackets 84 of the stationary guide-rails 12 previously described.

In order to minimize the amount of moisture and salt accretions on the back of the carrier plates, incident to the spraying operation, a vertically disposed partition plate 84 having a basal deflecting ledge 85 is supported within the casing adjacent to and parallel with the back of the vertical leg 22 of the carrier loop, and a transverse trough 86 having at one end a spout 87 leading to the drip pan, is arranged below the partition 84. Any spray going through the perforations of the carrier plates or between the gaps of adjoining plates runs down the partition and drips into the trough 86, which trough in turn, discharges its contents past the splint carrier into the drip pan.

The partition plate 84 is yieldably supported on the adjacent door 76 of the casing in such manner that when such door is closed the plate is caused to bear flatwise against the back of the carrier. Accordingly the plate 84 is connected to the door by a pair of

pivoted links 88 having depending tails 89 adjacent the inner side of the door, which door when closed bears against the tails and swings the links in a manner to press the plate 84 close to the opposing side of the carrier. (See Figs. 4 and 6.)

The trough 86 is preferably supported at its ends in pockets 90 formed adjacent the lower ends of the side posts 71. It is also sustained by straps 91 which depend from a cross-bar 92 connecting the lower ends of the posts 71, which bar affords a convenient support for the hinges of an overhanging cover-section 93 for an adjacent projecting portion of the drip pan wherein the splint carrier is flexed in its passage from a horizontal to vertical position. (See Figs. 1 and 5.)

We claim—

1. The combination with a travelling carrier constructed and arranged to support rows of projecting match splints, and means for guiding a portion of the carrier in a substantially vertical path, of a spraying element mounted laterally of and discharging horizontally toward the path of the splints, said element including a pendant member having longitudinal solution and air ports and having also a nozzle in communication with the lower ends of said ports, means supporting said member above the nozzle to permit bodily movement of the member and nozzle transversely of said path, and means for actuating said member.

2. The combination with a traveling carrier constructed and arranged to support rows of projecting match splints, and means for guiding a portion of the carrier in a substantially vertical path, of a pendant spraying element mounted laterally of and discharging horizontally toward the path of the splints, said element including a pendant member having longitudinal solution and air ports and having also a nozzle in communication with the lower ends of said ports, means supporting said member above the nozzle to permit bodily oscillatory movement of the member and nozzle transversely of said path, and means for oscillating said member.

3. The combination with a travelling carrier constructed and arranged to support rows of projecting match splints, and means for guiding a portion of the carrier in a substantially vertical path, of a horizontal rock-shaft supported adjacent said path, a head member and a pendulous arm fast on said shaft, said member having solution and air supply ports, a nozzle carried by said arm below the head member and arranged to discharge horizontally toward said path, said nozzle having solution and air ports, and said arm having longitudinal conduits between the corresponding ports of the head member and nozzle, and means for actuating said rock-shaft to oscillate said head member and

arm and thereby swing the nozzle transversely of said path.

4. The combination with a travelling carrier constructed and arranged to support rows of projecting match splints, and means for guiding a portion of the carrier in a substantially vertical path, of an element, including a nozzle, effective to spray the said splints with an impregnating solution, said element being mounted laterally of, and discharging horizontally toward the said path of the splints, a solution supply tank operatively connected with the spray nozzle, a drip receptacle located beneath the nozzle and the said path of the carrier, an overflow vessel for the said receptacle, and circulatory connections, including a pump, for the said vessel and supply tank.

5. The combination with a travelling carrier constructed and arranged to support rows of projecting match splints, and means for guiding a portion of the carrier in a substantially vertical path, of an element, including a nozzle, effective to spray the said splints with an impregnating solution, said element being mounted laterally of, and discharging horizontally toward the said path of the splints, a solution supply tank operatively connected with the spray nozzle, an overflow pipe extending from said tank, a drip receptacle located beneath the nozzle and the said path of the carrier, an overflow vessel for the said receptacle, and circulatory connections, including a pump, for the said overflow pipe, overflow vessel and supply tank.

6. The combination with a travelling carrier constructed and arranged to support rows of projecting match splints, and means for guiding a portion of the carrier in a substantially vertical path, of an element, including a nozzle, effective to spray the said splints with an impregnating solution, said element being mounted laterally of, and discharging horizontally toward the said path of the splints, a drip receptacle located beneath the nozzle and the said path of the carrier, a removable screen supported in said receptacle, and means for maintaining the liquid level in said receptacle normally above the screen.

7. The combination with a travelling carrier constructed and arranged to support rows of projecting match splints, and means for guiding a portion of the carrier in a substantially vertical path, of a pendant element, including a nozzle, effective to spray the said splints with an impregnating solution, said nozzle being mounted laterally of, and discharging horizontally toward the said path of the splints, means for oscillating said nozzle transversely of said path, a drip receptacle located beneath the nozzle and the said path, and a protective casing above said receptacle enclosing the pendant spraying ele-

ment and the adjacent portion of the carrier.

8. The combination with a travelling carrier constructed and arranged to support rows of projecting match splints, and means for guiding a portion of the carrier in a substantially vertical path, of a pendant element, including a nozzle, effective to spray the said splints with an impregnating solution, said nozzle being mounted laterally of, and discharging horizontally toward the said path of the splints, means for oscillating said nozzle transversely of said path, a drip receptacle located beneath the nozzle and the said path, a protective casing above said receptacle enclosing the pendant spraying element and the adjacent portion of the carrier, a vertically-disposed partition plate supported within the casing and adjacent to and parallel with the back of the carrier, and a trough below the partition plate leading to the drip receptacle.

9. The combination with a travelling carrier constructed and arranged to support rows of projecting match splints, and means for guiding a portion of the carrier in a substantially vertical path, of a pendant element, including a nozzle, effective to spray the said splints with an impregnating solution, said nozzle being mounted laterally of, and discharging horizontally toward the said path of the splints, means for oscillating said nozzle transversely of said path, a drip receptacle located beneath the nozzle and the said path, a protective casing above said receptacle enclosing the pendant element and the adjacent portion of the carrier, said casing having a door parallel with the back of the carrier, a partition plate, and link means for yieldably supporting said plate on the inner side of the door, whereby when the door is closed the plate is pressed toward the back of the carrier.

Signed at Oswego, in the county of Oswego and State of New York this 11th day of October, A. D. 1928.
